Specification of Letters Patent.

Patented Dec. 5, 1911.

Application filed June 13, 1908. Serial No. 438,345.

To all whom it may concern:

Be it known that I, IRA C. BUCKMINSTER, a citizen of the United States, residing at Beverly, in the county of Essex and Commonwealth of Massachusetts, have invented 5 certain Improvements in Presses, of which the following description, in connection with the accompanying drawings, is a specification, like reference characters on the drawings indicating like parts in the several figures.

This invention relates to presses in which the presser members are not only relatively movable in the pressing direction, but in 15 which they are also relatively movable in another direction or in other directions, and especially to presses in which the presser members are relatively movable into different pressing relations to work preferably 20 carried by one of said members.

In particular the invention relates to a press in which a pressure-applying member is movable into different pressure-applying relations to a bed upon which the work or 25 tool to which pressure is to be applied is supported.

In its illustrated preferred embodiment the invention is shown as applied to a press in which a work-supporting bed presents a 30 surface over which may be spread sheet material from which it is desired to die out blanks for manufacturing uses, for example, blanks for boots or shoes.

A machine of the general type of that 35 just referred to is illustrated in the U. S. Letters Patent to Arthur Bates, No. 921,503, granted May 11, 1909, and a general object of the invention is the improvement of the construction and operation of machines of 40 this type.

An important object of the invention is the provision of mechanism for effecting automatically the relative movement or movements which are necessary to bring the parts 45 of the machine into a desired relation to each other and which hitherto have usually been effected by hand, an important feature of the invention being the provision of such automatic mechanism in combination with 50 means for checking the relative movement when the parts have come into a desired relation to each other.

Another object of the invention is the provision in a machine of the type in which

a pressure applying member is movable over 55 a work supporting bed into different operative relations thereto, whether such movement be effected automatically or by hand, of means for checking this movement of the presser member in advance of or before 60 the end of its pressure applying movement. In its broadest aspects, this feature of my invention has been claimed in U. S. Letters Patent, 968,117, granted August 23, 1910, upon my co-pending application Serial No. 65 504,775, filed June 28, 1909. Such claims as are made herein will be directed, therefore, to subject-matter which is not common to the construction herein shown and that 70 shown in the said Letters Patent.

A further object of the invention is the provision of means controlled by the operator by which the directions and limits of the automatic relative movements above referred to may be determined by the operator 75 in advance of such movements. Preferably the relative movements of the presser members into and out of a selected operative relation are not necessarily equal, that is the relative movement of said members into 80 an operative relation does not necessarily bring them into the relation to each other in which they were before their relative movement into operative relation, and an important object of the invention is the provision of 85 mechanism co-operating with the above-mentioned controlling means for effecting automatically a relative movement of the presser members into the relation to each other which has been selected by the operator and 90 then effecting a relative movement of said members of uniform amount for successive operations into a different relation to each other, said second movement preferably 95 taking place in a direction different from that of said first mentioned movement.

The relative movement of the presser members out of the selected operative relation, which movement in the preferred form of the invention is constituted by a 100 movement of a pressure-applying member out of operative position over a die lying upon stock upon a co-operating bed, is preferably of an amount sufficient merely to move said member out of the way of the 105 operator while he is placing the die upon the stock for a successive operation. It will be seen therefore that an advantage of this

- construction in the usual method of operating machines of this type is that both the succeeding movement into operative position over the die in its new location and the succeeding movement out of operative position will be less than in a construction in which the member returns always to the same inoperative position, since the operator will usually place the die for a succeeding 10 operation upon a portion of the stock not remote from that upon which the previous operation was performed. The strain and jar due to the momentum acquired by the pressure-applying member in moving a long 15 distance over the bed into and out of operative position will thus be avoided.
- Other objects of the invention are the provision of mechanism whereby upon a single movement of a single device in a 20 single direction the parts of the machine may be brought automatically into a predetermined relation to each other, actuated to perform their functions, and then moved into a different relation to each other; the 25 provision of means for initiating the movements aforesaid which will itself be moved automatically out of the way of the operator and of the work at the end of said movements, the provision of a construction 30 in which the speed of the transmission of the movement of a constantly moving part to the parts of the mechanism to be actuated will be uniform for successive operations, but in which the amount of transmission 35 may be varied in accordance with the initial relative positions of the parts and the provision of means for preventing actuation of the mechanism except through the agency of the starting means.
- With the foregoing and other objects in view the invention is herein illustrated as embodied in a press of the type known to the trade as "clicking press", that is, a 40 press intended especially for dieing out boot and shoe blanks, one construction of this type of press being shown in the patent above referred to. In the press of the said patent a radial presser arm is provided which is movable by the operator into dif- 45 ferent operative relations to its bed. In the construction herein illustrated a radial presser arm is provided likewise movable into different operative relations to its bed, but combined with mechanism for moving 50 it automatically over its bed, together preferably with mechanism for stopping its further movement when it has come into a desired relation to said bed. Preferably, the mechanism for moving said member is 55 constructed to move said member automatically into an operative relation to the bed which has previously been selected by the operator and preferably without further 60 attention on the part of the operator effecting a pressure-applying operation of said 65

member and then moving it a sufficient distance to place it out of the way of the operator, this distance being preferably the same for successive operations.

The illustrated mechanism for effecting 70 in proper succession movements of the desired amounts for the above described purposes comprises constantly rotating mechanism and parts which are arranged to be clutched to said mechanism in succession by 75 means of a plurality of interrelated clutches. These clutches are preferably so arranged that when one of them is operated by means under the control of the operator the others will be operated automatically in a succes- 80 sion which is dependent upon the particular clutch first operated, the clutches being so connected to each other and to the parts which they clutch together that either the movement, usually of variable amount for 85 successive operations, which serves to bring the radial arm into the selected operative position over the bed, or the movement, preferably of uniform amount for successive operations, which serves to take it out 90 of such position, may be controlled by either of two clutches and that when one of said two clutches is thrown by the operator to cause the movement of variable amount into operative position the other clutch will be 95 thrown automatically at the proper time to cause the movement of constant amount out of said operative position.

In the illustrated preferred construction 100 a third clutch is provided and is arranged to be operated between the operations of the other two clutches without regard to the order in which said two clutches are operated, this third clutch serving to clutch together parts whereby a movement of the 105 radial presser arm toward and away from its bed to perform a pressure-applying operation may be effected.

As herein shown the two clutches through 110 which connections are made to effect horizontal movements of the radial presser arm over its bed are arranged to clutch loose gears to their respective vertical intergeared constantly rotating shafts, both of the loose gears shown being in mesh with a large gear 115 upon the column or shaft which carries the radial presser arm.

As hereinbefore suggested, an important feature of the invention is the provision of means for preventing further movement of 120 the pressure-applying member when it has come into a desired relation to its bed in combination with means for moving said member over said bed, and in the construction herein shown the means for preventing 125 further movement of said member comprises preferably braking means which is so constructed and arranged that it serves not only to prevent further movement of the member as it comes into the selected oper- 130

ative position, but also to prevent its further movement after it has been moved a predetermined distance away from the said operative position. The illustrated braking means is arranged to operate upon one of the loose gears, this arrangement of the braking means serving in the construction shown to bring its braking action to bear upon the member in whatever direction the member may be moving since the loose gear is always in mesh with the large gear upon the column or shaft which carries said member.

Inasmuch as the operator may desire at times to move the pressure-applying member, which in the illustrated construction is the radial presser arm, by hand into a different starting position from that in which it has been left by the automatic means, in the preferred embodiment the braking means is so constructed and arranged that the braking operation lasts only long enough to insure bringing the parts braked to rest and then ceases.

Other features of novelty which contribute to the carrying out of objects of the invention hereinbefore enumerated or to other objects of the invention which will be apparent from a consideration of the disclosure of the invention in the specification and drawings will either be pointed out in the following detailed description or included in the claims, or attention will be directed to them both in the specification and claims.

In the accompanying drawings,—Figure 1 shows in side elevation a press embodying the invention of this application; Fig. 2 is a view in rear elevation; Fig. 3 is a plan view of the press shown in Fig. 1; Fig. 4 is a detail view drawn to a larger scale of the four-armed lever and connected parts at the back of the machine; Fig. 5 is a horizontal section through the expanding ring clutch associated with the gears 32 and 38; Fig. 6 is a view, partly in vertical section, of the clutch associated with the gears 32 and 38, together with a view of the brake disk carried by the gear 32; and Fig. 7 is a detail section of the clutch associated with the gears 34 and 40 and also of the clutch which connects the brake eccentric to the gear 40.

Upon the base 2 of the frame of the machine is supported a head 4 having bearings for the vertical shaft or column 6 which carries the radial presser arm 8, said shaft or column 6 being mounted in said bearings in the head 4 both for oscillation about its axis and for reciprocation longitudinally of its axis. The presser arm 8 is arranged to oscillate with the shaft or column 6 to bring it into different operative relations to the cooperating presser member which, in the illustrated construction, is constituted by a stationary bed or block 10 supported upon a bracket 12 attached to the head 4.

The means for vertically reciprocating the shaft or column 6 may be and preferably is the same as that shown in the patent above referred to and comprises a spindle which is swiveled in the column 6 and is linked to an eccentric upon the main shaft 14 to which a normally loose belt pulley 16 may be clutched by an expanding ring or other suitable clutch. Carried by the pulley 16 is a bevel gear 18 meshing with another bevel gear 20 on a cross shaft 22. A second bevel gear 24 on the cross shaft 22, or formed on the gear 20, meshes with a bevel gear 26 on a vertical shaft 28, the shaft 28 being thus kept constantly rotating while the belt pulley 16 is connected to a source of power.

The vertical shaft or column 6 carries near its upper end a large segment gear 30 by which it may be oscillated to bring the radial presser arm 8 into different pressing relations to the bed 10. Meshing with the segment gear 30 are gears 32 and 34, the gear 32 being mounted on the shaft 28 and arranged to be clutched thereto by an expanding ring clutch associated with said gear. The gear 34 is mounted on a second vertical shaft 36 in the upper part of the head 4 and is arranged to be clutched thereto by an expanding ring clutch associated with said gear, the shafts 28 and 36 being connected together by gears 38 and 40 of equal diameter and rigidly attached to the respective shafts. The clutches for the gears 32 and 34 are operated from the centers of the respective shafts 28 and 36, two operating mechanisms being provided for each clutch.

The constructions of the corresponding operating mechanisms of the two clutches are substantially the same, so that a description of the two operating mechanisms in the clutch shown at the right in Fig. 2, at the left in Fig. 3 and in detail in Figs. 5 and 6 will apply equally as well to the operating mechanisms of the clutch associated with the gear 34, the reference characters applied upon the drawings to parts of the latter clutch being the same as those applied to corresponding parts of the other clutch except that they are primed.

Attached to the hub of the gear 32 is a disk 42 having a depending flange 44 concentric with the shaft 28, extending within the rim of the gear wheel 38 and surrounding an expanding ring 46 attached at one end to said gear wheel 38 by screws 48. A lever 50 pivoted at 52 upon the gear 38 has one arm extending into a recess in one side of the shaft 28 and another arm in engagement with the other end of the ring 46. Movement away from the center of the shaft 28 of the end of the lever 50 which extends into the recess in said shaft serves to expand the ring 46 and thereby to clutch the gear 32 to the gear wheel 38 and shaft 130

28. Such movement of the lever 50 may be effected through either one of two mechanisms.

If the movement of the radial arm 8 into operative position is to be effected through the gear 32, and if, therefore, it is desired that a movement be imparted to segment gear 30 which is proportional to the distance the arm 8 will have to travel to come into such operative position, clutching of the gear 32 to the gear wheel 38 and shaft 28 will be effected by the action of a pin or plunger 54 slidably mounted in a central bore in the upper end of the shaft 28, and having a tapered lower end arranged to engage a beveled side of the end of the lever 50 which projects into the recess in the side of said shaft and when depressed to force this end of the lever away from the center of said shaft and thereby expand the ring 46 into engagement with the flange 44 to effect a clutching of the gear 32 to the gear wheel 38 and shaft 28.

In the illustrated preferred embodiment 25 of the invention, the means for depressing the pin or plunger 54 to effect a clutching of the gear 32 to the gear wheel 38 and shaft 28 comprises a lever 56 pivoted upon the upper part of the head 4, one end of the lever 56 bearing upon the upper end of pin 54 and the other end being operatively connected by a rod 58 to one arm of a second lever 60 pivoted at 62 upon the side of the head 4, the lower end of the rod 58 resting 35 in a socket in the lever 60. The other arm of the lever 60 is normally kept in its raised position by a spring 64 surrounding a rod 66 connected at its lower end to the lever 60 and having threaded on it a nut 68 between which and a guiding lug 70 on the head 4 the spring 64 is confined. Depression of the normally raised front end of the lever 60 to effect through rod 58, lever 56 and pin 54 a clutching of the gear 32 40 to the gear wheel 38 and shaft 28 may be effected, in the construction shown, through a cam 72 formed upon or carried by a collar 74 rotatably mounted upon a depending boss of the head 4 surrounding the vertical shaft or column 6.

Rotation of the collar 74 to the left in Fig. 3 serves to bring the cam 72 into engagement with the upper end of and to depress a rod 76 vertically guided in ears 78 55 upon the radial arm 8, the reduced lower end of the rod passing through and being riveted to the hub 80 of one half of a split ring 82, a roll upon the front end of the lever 60 bearing against the under side of 60 the ring 82. The depression of the rod 76 is transmitted through the left-hand half of the ring 82 to the front end of the lever 60 and through rod 58, lever 56 and pin 54 65 serves to operate the clutch which clutches the gear 32 to the shaft 28. The direction

of rotation of the shaft 28 is such that when the just-mentioned clutching is effected the gear 32 will rotate through the segment gear 30 the shaft or column 6 in a direction to cause the arm 8 to carry the rod 76 around 70 until its upper end rides back up over the cam 72 under the influence of the spring 64 on the rod 66 and lever 60. When the upper end of rod 76 again comes into its uppermost position the lever 60 will have turned about its pivot sufficiently to permit the clutch to be released, whereby the arm 8 will be permitted to come to rest.

The collar 74 carries an arm 84 by which it may be turned by the operator to bring 80 its cam 72 into various angular positions with respect to the axis of the vertical shaft or column 6, and means is carried by the arm 84 for effecting a locking of the arm and collar in the various angular positions to 85 which it is turned.

The illustrated locking means comprises a rod 86 slidably mounted in ears upon the arm 84 and pressed by a spring 88, surrounding the rod 86 and confined between 90 one of the ears and a collar upon said rod, normally toward the shaft 6, the end of the rod remote from the operator being shaped to engage, when they are brought into operative relation to it, one of the teeth 90 upon 95 a segment plate 92 normally held in its uppermost position by a spring 93 surrounding one of the supporting stems 94 of the plate, said spring resting in a socket in the frame and bearing against a shoulder on 100 said stem. The upper end of the stem 94 has a pin and slot connection with the forward end of a lever 95 pivoted at 96 upon the head 4 and connected between its pivot and front end with the rod 66.

It will be seen from the foregoing description that the segment plate 92 is normally kept out of operative locking relation to the end of the rod 86 remote from the operator. When, however, the collar 74 is turned by 110 the operator to bring the cam 72 into such position that it will depress the rod 76 the segment plate 92 will be lowered and its teeth will be brought into such position that the end of the rod 86 may engage with them. Before, however, the segment plate 92 can be lowered the rod 86 must be withdrawn from beneath it since its end remote from the operator, as shown, is constructed to prevent an accidental lowering of this plate 120 and an accidental starting of the machine. In the illustrated preferred construction movement of the end of the rod from beneath the segment plate 92 is effected automatically as the operator grasps the handle 125 98 by which he turns the collar 74. As shown in Fig. 3, the enlarged end of the rod nearest the operator is provided upon opposite sides of its axis with arc-shaped slots 100 and 102 in which travel pins 104, 130

106 upon opposite sides of the handle 98, said handle being pivoted at 108 upon the arm 84. As the operator grasps the handle 98 to turn the collar 74 toward the left in Fig. 3, it will be seen that the pin 106 will engage the end of the slot 102 in which it is located and will pull the rod 86 toward the operator as the handle 98 turns about its pivot 108, the pin 104 in the meantime traveling freely in its slot 100. When the handle 98 is grasped by the operator to move the arm 84 in the other direction, the operations of the pins in their slots will be reversed.

The parts hereinbefore described which 15 control the movement of the arm 8 in one direction into operative position have upon the other side of the machine substantial duplicates which control the movement of the arm in the other direction into operative 20 position and these duplicate parts are indicated upon the drawings where shown by corresponding reference characters primed.

The segment plate 92 is not divided into two parts after the manner of the ring 82 25 but is continuous throughout its extent. The plate is, however, provided with two supporting stems 94, 94', which have pin and slot connections with the respective levers 95 and 95'. The pins upon the ends of the 30 levers 95, 95' rest normally in the bottoms of the slots in the stems 94, 94', so that when either lever is operated to depress the plate 92 against the action of its supporting springs the slot in the stem connected to 35 the other lever will pass freely over the pin on said lever and thus not disturb the position of said lever.

From the foregoing description it will be seen that when the arm 84 is turned toward 40 the left in Fig. 3 it will cause the cam 72 to depress the rod 76 and the left-hand half of the split ring 82 and thereby operate the clutch which connects the gear 32 to the gear wheel 38 and shaft 28, so that the arm 8 will 45 also be moved toward the left in this figure. When, however, the arm 84 is moved toward the right in Fig. 3 it will cause the cam 72' to depress the rod 76' and the right-hand half of the split ring 82, and through the 50 lever 60' and rod 58', lever 56' and pin 54' operate the clutch which connects the gear 34 to the gear wheel 40 and the shaft 36, and thereby cause the arm 8 to be moved toward the right in this figure.

55 As hereinbefore pointed out, the arm 8 will move in either direction only until it brings the rod 76 or rod 76' into such a position that it rides up over the cam 72 or cam 72' according as the rod 76 or rod 76' has been depressed. To prevent the momentum acquired by the arm 8 in its movement from carrying it beyond the point at which the rod 76 or the rod 76' rides up over its corresponding cam, brake mechanism 60 has been provided which operates upon

one of the gears connected to the segment gear 30 and thereby serves to stop the rotation of the arm after the actuating gear has been unclutched from its shaft. In the illustrated embodiment, this brake mechanism is 70 arranged to operate upon the gear 32 and comprises grooved jaws 110, 112 pivoted at one end at 114 upon the frame of the machine and arranged to embrace a disk 116 upon the hub of the gear 32, the disk 116 75 having a periphery which is V-shaped in cross-section to fit the grooves in said jaws.

The mechanism for opening and closing the jaws 110, 112 to cause them to release or grip the disk 116 comprises a lever 118 80 fulcrumed upon the end of the jaw 112 remote from its pivot and connected by a link 120 to the end of the jaw 110 remote from its pivot. The arm of the lever 118 to which the link 120 is connected projects beyond the 85 end of the jaw 110 so that when this arm of the lever moves toward the front of the machine, as shown in Fig. 3, it will serve to draw the jaws together and cause them to exert a braking action upon the disk 116, 90 and when it is moved toward the rear it will cause the jaws to open.

Means is provided for effecting automatically, through the described opening and closing mechanism, the closing of the jaws 95 to brake the disk 116 as the arm 8 reaches its desired limit of movement in either direction, and this means, in the illustrated construction, comprises an eccentric 122 surrounding the hub of the gear wheel 40 and 100 arranged to be clutched to this gear wheel. An eccentric collar 124 surrounding the eccentric 122 is yieldingly connected at 126 to the other arm of the lever 118.

Rotation of the eccentric 122 after it has 105 been clutched to the gear wheel 40 operates first to apply the brake to the disk 116 and then to release the brake just before the eccentric is unclutched from the gear wheel 40. The means for effecting the clutching of the 110 eccentric 122 to the gear wheel 40 comprises a pin 128 carried by the eccentric 122 and spring-pressed toward the gear wheel 40, the gear wheel 40 having an opening adapted to receive the end of the pin 128 when the 115 pin has been released and the opening has come into proper relation to it.

The pin 128 is normally held out of clutching relation to the gear wheel 40 by the engagement with a projection on said pin of 120 the wedge-shaped end of a lever 130 pivoted upon the frame of the machine and connected at its other end to a link 132 connected to an arm 134 attached to a rock-shaft 136 mounted in bearings on the head 125 4. The wedge-shaped end of the lever 130 is arranged to enter between the under surface of the eccentric 122 and the said projection on the clutch pin 128 and thereby cause the pin to be pulled away from the 130

gear wheel 40 against the tension of its spring. A second arm 137 attached to the rockshaft 136 carries a pawl 138, spring-pressed toward a collar 140 clamped to the rod 58. When the rod 58 is raised by the depression of the forward end of the lever 60 to effect a clutching of the gear 32 to the shaft 28 and thereby rotation of the arm 8 toward the left in Fig. 3, the pawl will 10 spring under the collar 140.

After the arm 8 has rotated far enough to cause the upper end of the rod 76 to ride up over the cam 72 the lowering of the rod 58 by the action of the spring 64 upon the 15 forward end of the lever 60 will cause the collar 140 to depress the arm 137 to which the pawl 138 is attached, and through the arm 134 and link 132 move the wedge-shaped end of the lever 130 out of operative 20 relation to the clutch pin 128, thus permitting the pin to drop into the pin receiving recess of the gear wheel 40 when the gear wheel is turned to bring this recess into proper relation to the pin, and thereby effecting 25 a clutching of the eccentric 122 to the gear wheel 40.

Turning of the eccentric 122 with the gear wheel 40 serves during the first half of its rotation to effect a braking of the gear 30 32 and through it of the segment gear 30 by the closing of the jaws 110, 112 upon the disk 116, thereby serving to stop the arm 8 in the position to which it has been moved by the gear 32. The eccentric 122 remains 35 clutched to the gear wheel 40 for only one rotation of said gear wheel. The unclutching of the eccentric 122 from the gear wheel 40 at the end of this rotation is effected through the following mechanism:

40 Connected by link 142 to the joint 126 between the eccentric collar 124 and the lever 118 is an arm 144 fast upon a rockshaft 146 which carries at its outer end a pawl-tripping arm 148 arranged to engage the tail of 45 the pawl 138. As the eccentric 122 rotates with the gear 40 after it has been clutched to said gear by the release of the pin 128, the arm of the lever 118 to which the eccentric collar 124 is connected is moved first to 50 ward the rear, thereby turning through the link 142 and arm 144 the rockshaft 146 in a direction to cause the pawl-tripping arm 148 to move the pawl 138 from beneath the collar 140.

55 As soon as the pawl has been moved from beneath the collar 140 a spring 150, attached to the arm 134, moves said arm in a direction to cause the wedge-shaped end of the lever 130 to come into unclutching relation

60 to the clutch pin 128, so that when the eccentric 122 has rotated to bring the pin 128 into operative relation to the wedge-shaped end of the lever 130 the pin will be withdrawn from its recess in the gear wheel 40 65 and the eccentric will be unclutched from

said gear wheel. It will be noted from the foregoing description that this unclutching takes place at the same point at which the clutching took place, and that the eccentric is at this time in its brake releasing position. 70

The brake is therefore released from the disk 116 and the gear 32 is free to be rotated. This is an important provision, especially when the brake has just operated to brake 75 the end of the movement of the arm 8 out of the operative position in which it performed a pressure-applying operation, inasmuch as it leaves the arm 8 free to be moved by the operator. It will be understood that 80 the foregoing description applies equally to the corresponding parts on the other side of the machine, and that the rockshaft 136 has a pawl-carrying arm at each end, one arm carrying a pawl 138 to engage with a collar 85 140 upon the rod 58 and the other arm carrying a pawl 138' to engage with the collar 140' upon the rod 58'. It will be further understood that the rockshaft 146 carries a pawl-tripping arm at each end to trip the 90 pawls above referred to.

After the arm 8 has been brought into the desired operating position over the bed, it is actuated to perform a pressure-applying operation and such actuation preferably 95 follows automatically its location in the desired operative position.

In the illustrated embodiment, the automatic actuation of the arm 8 to perform a pressure - applying operation is effected 100 through the following mechanism: The vertical shaft or column 6 is connected to suitable reciprocating mechanism operated from the shaft 146, the said mechanism being preferably the same as that disclosed in the 105 U. S. Letters Patent 921,503, above referred to. The belt pulley 16 is preferably arranged to be clutched to the shaft 14 to effect an actuation of the reciprocating mechanism for the shaft 6, and this clutch 110 mechanism is preferably that disclosed in the co-pending application of Arthus Bates, Serial No. 443,060. Included in this clutch mechanism is a member 152 which releases a pin of a one rotation clutch at the end of 115 one rotation of the shaft 14 by the pulley 16, and this member is arranged to be lifted out of its pin releasing position to cause a clutching of the pulley 16 to the shaft 14 by a lever 154 having a catch plate 156 arranged to engage under a catch plate 158 upon a lifting arm 160 pivoted upon the member 152 and yieldingly pressed toward the end of the lever 154.

In the illustrated construction, the machine is arranged to stop with the shaft 14 unclutched from the pulley 16 and with the lever 154 in such position that its catch plate 125 156 lies above the catch plate 158. It will be seen, therefore, that lifting of the lever 130

154 when it is in this position will not have any effect upon the member 152. In order that the member 152 may be lifted out of its clutch releasing position, the catch plate 156 must be brought beneath the catch plate 158.

In the illustrated construction, movement of the lever 154 into position to bring its catch plate 156 beneath the catch plate 158 is effected through the following mechanism: Pivoted upon the back of the machine is a lever 162 which is connected at one end by a link 164 to the lever 154 and at its other end by a link 166 to the lever 60. As the rear end of the lever 60 is raised when the rod 76 is depressed to effect a clutching of the gear 32 to the shaft 28, the end of the lever 162, to which the link 164 is attached, will be lowered and the lever 154 will therefore be lowered to bring its catch plate 156 beneath the catch plate 158. When the rod 76 has been carried by the arm 8 into such position that its upper end rides up over the cam 72, thereby permitting the forward end of the lever 60 to be raised by the spring 64 and the rear end to be again depressed to effect an unclutching of the gear 32 from the shaft 28, the end of the lever 162 to which the link 164 is attached will be raised and the lever 154 will be raised, thereby lifting the member 152 out of clutch releasing position and effecting a clutching of the pulley 16 to the shaft 14. This clutching of the pulley 16 to the shaft 14 effects an actuation of the reciprocating mechanism for the shaft or column 6, and thereby a pressure-applying operation of the arm 8. It will be noted that this actuation of the mechanism for causing a pressure-applying operation of the arm 8 takes place simultaneously with the clutching of the brake applying eccentric 122 to the gear wheel 40 and that, therefore, the pressure-applying operation starts at the same time that the braking of the movement of the arm into operative position is effected, so that no time is wasted between the movement of the arm into operative position and its actuation to perform a pressure-applying operation.

50 It will be understood that there are two levers 154 and 154' either of which may be moved into a position to cause its catch plate 156 or 156' to catch beneath the catch plate 158 upon the lifting arm 160.

55 It will be further understood that the lever 154' is connected by a link 164' to one end of a lever 162' which is connected at its other end by a link 166' to the lever 60', the arm 154' effecting the clutching of the pulley 16 to the shaft 14 after the arm 8 has been moved by the gear 34 into its desired operative position. After the arm 8 has been actuated to perform a pressure-applying operation it is preferably moved automatically into an inoperative position

or into a position not over the portion of the work upon which the pressure-applying operation has been performed, and the pressure-applying operation and the automatic movement of the arm out of the operative position in which the pressure-applying operation has been performed preferably take place in automatic succession.

In the illustrated embodiment, the movement of the pressure-applying member out of the operative position in which the pressure-applying operation has been performed is effected through that one of the two loose gears which has not been utilized to move the member into operative position, and mechanism is provided which is operated upon the return of the pressure-applying member to its uppermost position after effecting the pressure-applying operation to effect a clutching to its shaft of the gear 85 which is to cause the movement of the pressure-applying member out of the operative position in which it has effected the pressure-applying operation.

The illustrated mechanism comprises a lever 168 forked at its forward end and having pins entering from opposite sides a circumferential groove in a collar 170 attached to the adjusting rod 172 carried by the shaft or column 6. The lever 168 is pivoted at 174 upon the head of the machine and at its rear end is connected by a rod 176 to one end of a multiplying lever 178 pivoted upon the back of the machine, the other end of said lever being connected by a link 180 to a second-class lever 182 pivoted at 184 upon the back of the machine and carrying a spring-pressed pawl 186 adapted to slip under a tooth 188 upon a slide plate 190 when the lever 182 is depressed and to engage said tooth when the lever is raised and raise with it the said slide plate.

Fulcrumed upon the slide plate 190 at 192 is a four-armed lever arranged to travel up and down with the slide plate 190 and to be tilted with respect to said slide plate to bring it into different relations to the operating mechanisms for the clutches to be hereinafter described. The arm 194 of the four-armed lever is connected by a link 196 to the lever 60, the connection between the arm 194 and link 196 being a pin and slot connection and the length of the slot being substantially equal to the extent of the vertical movement of the slide 190. The arm 194' is connected by a link 196' to the lever 60', the connection between the arm 194' and the link 196' being similar to that between the arm 194 and the link 196.

If the forward end of the lever 60 is depressed by the action of the cam 72 on the rod 76 to effect a clutching of the gear 32 to the shaft 28, the link 196 will be raised and the four-armed lever will be turned about its fulcrum 192 into the position shown

in Fig. 4. In this position the end of the arm 198' of the four-armed lever will lie vertically beneath a lifting plate 200' carried by the clutch-actuating rod 202' and the end of the arm 198 will be moved out of its vertical position beneath the lifting plate 200 on the clutch actuating rod 202. The four-armed lever will remain in this position until it is tipped in the other direction by movement of the lever 60'. When the arm 8 has been actuated to perform the pressure-applying operation the lever 182 will first be lowered to bring its pawl 186 under the tooth 188 of the slide 190 and then raised upon return of the arm 8 to its uppermost position, thereby lifting with it the slide 190 and the four-armed lever. As the slide 190 is raised by the lever 182 the arm 198' will engage the lifting plate 200' and move the clutch actuating rod 202' upward, thus effecting an actuation of the clutch controlled by it. The movement imparted to the lever 182 through its connections with the adjusting rod 172 is sufficient so that when the slide 190 reaches the upper limit of its movement the lever 182 will continue to move until the pawl 186 is brought out of engagement with the tooth 188. The slide 190 is thus permitted to return to its lowermost position carrying with it the four-armed lever.

It will be seen from the foregoing description that if the rod 76' is depressed by the cam 72', thereby depressing the forward end 35 of the lever 60', the link 196' will operate to tip the four-armed lever toward the right in Fig. 4, thereby bringing its arm 198 beneath the lifting plate 200 upon the clutch operating rod 202 and causing the clutch 40 controlled by it to be operated instead of the clutch controlled by the rod 202'.

The clutch operating rod 202 is connected at its upper end to one arm of a lever 204 pivoted upon the machine head and forked 45 at its other end to embrace a collar 206 formed upon or attached to the upper end of a clutch actuating sleeve 208 which surrounds the clutch actuating pin 54 and is tapered at its lower end where it engages the 50 beveled end of the lever 50. The collar 206 has upon its upper face at one side a depression 210 provided with inclined side walls, and a correspondingly shaped projection upon the frame adjacent to the collar fits 55 normally into the depression in the collar.

The collar 206 with its sleeve 208 is held normally in its uppermost position by a spring 212 surrounding the sleeve 208 and extending between the lower face of the collar 206 and a flange 214 upon the upper end of the shaft 28. When the collar 206 and its sleeve 208 are depressed by the action of the rod 202 on the lever 204, thereby serving to move the inner end of the lever 50 away from the center of the shaft 28 and to

effect the clutching of the gear 32 to the gear wheel 38 and shaft 28, a pin 216 upon the under side of the collar 206 is engaged by a pin 218 upon the flange 214 of the shaft 28 and the collar 206 and sleeve 208 are rotated with the shaft 28, thus preventing the projection upon the frame from again entering the depression 210 upon the upper face of the collar until the collar and its sleeve have made a complete rotation with the shaft 28. 75 It will thus be seen that the clutch which is operated by the upward movement of the rod 202 under the influence of the arm 198 of the four-armed lever is a one rotation clutch. The clutch operated by the rod 202' 80 is similar in construction and operation to that operated by the rod 202 and the foregoing description with primed reference numerals will apply equally as well to it.

Since the gear which is clutched to its 85 shaft to effect the movement of the arm 8 out of the operative position in which it has performed the pressure-applying operation is clutched to the shaft for one rotation only, this movement from operative into inoperative position of the arm will be the same for successive operations. 90

When the clutch which serves to clutch one of the gears 32, 34 to its shaft to effect the movement of the arm 8 out of the operative position in which it has performed the pressure-applying operation is released, mechanism is preferably provided for applying the hereinbefore described brake to the gear 32 in the same manner that it is 100 applied at the end of the movement of the arm 8 into its operative position. This mechanism preferably comprises, for the most part, the same mechanism as that used to effect an application of the brake at the 105 end of the said movement into operative position. Upon the rod 202 is carried a collar 220 into engagement with the under side of which a pawl 222 mounted upon the arm 137 attached to the rockshaft 136 is adapted to be pressed by its spring when the rod 202 is raised to operate the clutch controlled by it. As the rod 202 is again depressed by the action of the spring 212 in returning the collar 206 and sleeve 208 to their uppermost 110 position at the end of a complete rotation of the shaft 28, the rockshaft 136 is rocked in the direction to effect through its connections with the lever 130 an application of the braking jaws to the disk 116 in the manner hereinbefore described. 115

The description of the operation of the separate mechanisms has been included in the detailed description of these mechanisms. The operation of the machine as a 120 whole will now be briefly set forth. The operator, having selected a die 11 of the shape of the desired blank to be died out from the stock, places it upon the stock upon the bed 10 over a portion of said stock 130

which has been selected by him as most suitable for the said blank, the radial pressure-applying arm 8 being at this time out of operative relation to the die. If the operator in laying the die upon the stock finds that the arm 8 is over any part of the stock upon which he desires to lay the die, he can easily push the arm out of this position, since the arm, when the machine is not in 10 operation, is free to rotate with the vertical shaft or column 6. Having placed the die 11 in the selected location upon the stock, the operator grasps the handle 98 and swings the arm 84 in the direction to bring 15 it over the die 11. As the operator starts to move the arm 84, the handle 98 turns about its pivot 108 in one direction or the other according to the direction in which the arm 84 is to be moved and through the 20 pin 104 or 106 draws the locking rod 86 from beneath the locking plate 92. This movement of the rod 86 from beneath the plate 92 permits the plate 92 to be depressed as the cam 72 or the cam 72' engages the upper end of the rod 76 or the rod 76' to depress the forward end of the lever 60 or the lever 60'. When the arm 84 has been turned far enough to bring it into the desired position over the bed 10 and die 11 the operator 25 releases the handle 98 and the spring 88 moves the locking rod 86 again toward the locking plate 92, thus bringing its end remote from the operator into engagement with one of the teeth 90 of said plate, there- 30 by locking the arm 84 in the position to which it has been moved. Assuming that the arm 98 has been moved toward the left in Fig. 3, the forward end of the lever 60 will be depressed by the engagement of cam 35 72 with the upper end of rod 76, and the rear end of the lever 60 will be raised, thus, through the rod 58, lever 56 and pin 54 clutching the gear 32 to the shaft 28. Raising of the rear end of the lever 60 also raises 40 the end of the lever 162 to which it is connected by the link 164 and depresses the other end of this lever, thus permitting the catch plate upon the lever 154 to come beneath the catch plate upon the lifting arm 45 160. The gear 32 having been clutched to the shaft 28 will rotate the segment gear 30, thereby causing the arm 8 to turn toward the left in Fig. 3 until it brings the rod 76 into such position that it rides up over the 50 cam 72 thereby effecting an unclutching of the gear 32. Lifting of the rear end of the lever 60 serves also through the link 196 to tip the four-armed lever into the position shown in Figs. 2 and 4, whereby its arm 198' 55 is brought beneath the lifting plate 200'. As the rod 58 has been raised by the upward movement of the rear end of the lever 60, the pawl 138 upon the arm 137 has 60 caught beneath the collar 140 on said rod.

As the arm 8 swings into the position to cause the upper end of the rod 76 to ride up over the cam 72, the spring 64 lifts the forward end of the lever 60 and the rod 76 and depresses the rear end of the lever, thereby effecting an unclutching of the gear 70 65 from the shaft 28, rocking of the rock-shaft 136 through the action of the collar 140 upon the pawl 138, clutching of the brake eccentric 122 to the gear 40 and the braking of the movement of the arm 8 through the 70 action of the brake jaws 110, 112 upon the 75 brake disk 116 carried by the gear 32. Depression of the rear end of the lever 60 also depresses the end of the lever 162 to which it is connected and raises the other end, 80 thereby raising the lever 154 which carries with it the lifting arm 160 and brings the clutch releasing member 152 out of operative 85 relation to the clutch between the shaft 14 and the pulley 16. The clutch between the shaft 14 and pulley 16 is thus permitted to act and these parts are clutched together for one rotation of the pulley 16. The movement of the pulley 16 being thus transmitted to the shaft 14 effects through the 90 shaft 14 a vertical reciprocation of the vertical column or shaft 6, together with the radial pressure applying arm 8. The movement of the shaft or column 6 downward to bring the pressure applying arm 8 into 95 contact with the die 11 operates through the connections 168, 176, 178, 180 to move the lever 182 downward about its pivot and thus bring its pawl 186 into engagement with the under side of the teeth 188 upon the slide 100 plate 190. Return of the shaft 6 to its uppermost position effects through the same connections a movement of the lever 182 in the opposite direction, thus raising the slide plate 190 and through the arm 198' of the 105 four-armed lever carried by said plate, the lifting plate 200', the clutch-actuating rod 202' and connections 204', 206', 208', effecting a clutching of the gear 34 to the shaft 36 for one rotation of said shaft. Inasmuch 110 as the shaft 36 rotates in a direction opposite to that of the shaft 28, the gear 34 will be rotated in the direction opposite to that of the gear 32 and the segment gear 30 will likewise be turned in a direction different 115 from that in which it turned in bringing the arm 8 into operative position over the die 11. When the gear 34 is unclutched from the shaft 36 at the end of one complete rotation of said shaft, the return of the rod 202' to its lowermost position operates through the sleeve 220' and pawl 222' upon the arm 137' corresponding to arm 137 to 120 effect a clutching of the brake eccentric 122 to the gear 40 and an application of the 125 brake jaws 110, 112 to the disk 116 upon the gear 132.

As hereinbefore pointed out, the jaws 110

and 112 are moved out of braking relation to the disk 116 before the eccentric 122 is unclutched from the gear 40 at the end of one complete rotation of said gear. This 5 leaves the arm 8 free to be turned with the shaft 6 to any position with respect to the bed in which the operator may desire to have it, provided its automatic movement out of operative position over the die has left it 10 in an undesirable relation to the bed. The movement into an inoperative position imparted by one complete rotation of the gear 32 or the gear 34 is usually sufficient to take the arm entirely out of the way of the operator, so far as the succeeding die placing 15 operation is concerned. It may happen, however, that the operator desires to lay the die upon a portion of the stock remote from that last died out and in such case he may 20 desire to have a different movement of the arm from that automatically provided. For this reason the arm is left free to be moved by the operator when the parts come to rest. Moreover, it will be understood that, 25 although means is provided for automatically moving the radial pressure applying arm or presser member 8 into the selected operative position, the operator is not necessarily restricted to the above described mode 30 of operation of the machine. The radial arm or presser member being free to move at all times except when connected to the mechanism by which its automatic movements are effected, the operator may, if he 35 desires, swing said arm or member into the selected operative position by hand and thereafter actuate the mechanism through which the pressing operation and the movement out of operative position are automatically 40 effected. When it is desired to operate the machine in this manner the operator will grasp the handle 98, after the radial arm or presser member 8 has been swung by hand into the selected operative position, 45 and swing the arm 84 slightly to one side or the other, the direction in which the operator swings the arm 84 depending upon the desired direction of the movement of the radial arm or presser member 8 into inoperative 50 position. As above pointed out the movement of the arm 84 will cause the cam 72 or the cam 72' to depress the associated rod 76 or 76' and initiate the movement of the automatic mechanism hereinabove 55 described, the various operations performed by this mechanism thereafter taking place in automatic succession. The radial arm or presser member 8 being already in operative position the arm 84 will be swung to one side 60 only far enough to effect the actuation of the automatic mechanism and will then be returned to its position over the radial arm or presser member before the said mechanism has operated to effect a lateral movement of said arm or member, and thus the

radial arm or presser member will be caused to perform the pressing operation in the position to which it has been moved by hand.

It will be noted that an important feature of the invention which contributes to the compactness of the construction illustrated is the provision with a single clutch of two operating means for said clutch, one of which operates the clutch in such manner that it clutches two parts together for a movement proportional to the movement of a part included in said operating means, and the other of which operates said clutch in such manner that it acts as a one rotation clutch. After the clutch has been operated which moves the arm 8 into its operative position over the die, thus bringing the arm 8 beneath the arm 84, the release of the clutch permits the plate 92 to be moved back to its uppermost position by its springs 93, thus permitting the remote end of the locking rod 86 to be moved back beneath said plate. When the remote end of the rod 86 is in position beneath the plate 92, neither the rod 76 nor the rod 76' 90 can be depressed by the cam 72 or the cam 72' and therefore when the arm 8 is moved out of its operative position over the die by the gear which has not been clutched to its shaft to move said arm into operative position the arm 84 will be carried with the arm 8 and will come to rest in a central position above the arm 8. This movement of the arm 84 with the arm 8 serves to take it out of the way of the operator simultaneously with the movement of the arm 8 for this same purpose.

It will be noted further that this movement of the arm 84 with the arm 8, when the arm 8 moves out of its selected operative position, serves to leave the arm 84 in such position that when the handle 98 is grasped by the operator to move the arm 84 over the die 11, it being immaterial into what new location with respect to the die the arm 8 has been moved, the said movement of the arm 84 will serve to operate the proper clutch for effecting the movement of the arm 8 in the direction to bring it over the said die.

Having described my invention, what I claim as new and desire to secure by Letters Patent of the United States is:—

1. A machine of the class described, comprising coöperating presser members relatively movable into different operative relations to each other, means for effecting a relative pressure applying movement of said members, starting means under the control of the operator, and means separately controlled from said starting means for preventing a continuation of the first-mentioned relative movement of said members during the last-mentioned relative movement of said members.

2. A machine of the class described, comprising a bed, a die freely movable over said bed, a pressure applying member having a pressure surface area less than that of the bed and movable into and out of operative position over said die wherever located on the bed, means for moving said member toward and away from the bed to cause it to engage the die and effect a pressing operation and automatic means for checking the movement of the member over the bed in advance of the pressing operation constructed and arranged to operate also at the end of the movement of said member 15 out of operative position.

3. A machine of the class described, comprising coöperating presser members arranged for relative movements in amounts determined at the will of the operator to bring them into different operative relations to each other, means for automatically effecting the relative movement of said members, and means for preventing further relative movement when said members have 25 come into a selected operative relation.

4. A machine of the class described, comprising a bed, a pressure-applying member arranged for movement over said bed in amounts determined at the will of the operator to bring it into various operative relations to said bed, means for automatically moving said member over said bed, and means for preventing further movement of said member as it comes into a selected relation to said bed.

5. A machine of the class described, comprising a bed, a pressure-applying member movable over said bed into various operative relations thereto, means for automatically moving said member over said bed, and braking means for preventing further movement of said member as it comes into a selected relation to said bed.

6. A machine of the class described, comprising coöperating presser members arranged for relative movement in amounts determined at the will of the operator to bring them into different operative relations to each other, and means for automatically effecting relative movement of said members comprising mechanism constructed and arranged to be automatically disconnected after a desired amount of relative movement of said members.

55 7. A machine of the class described, comprising coöperating presser members, arranged for relative movement in amounts determined at the will of the operator to bring them into different operative relations 60 to each other, means for automatically effecting relative movement of said members comprising mechanism constructed and arranged to be automatically disconnected after a desired amount of relative movement of said members, and means for pre-

venting further relative movement of said members after said mechanism has been disconnected.

8. A machine of the class described, comprising a bed, a pressure-applying member movable into various operative positions thereover, means for automatically moving said member out of its selected operative position constructed to effect a fixed amount of such movement, and braking means associated with said moving means.

9. A machine of the class described, comprising a bed, a pressure-applying member movable into various operative positions thereover, means for automatically moving said member, means for determining in advance of the automatic movement of said member the extent and direction of such movement, and braking means for stopping the movement of said member as it comes 85 into a selected operative position.

10. A machine of the class described, comprising a bed, a die movable over said bed, a pressure-applying member movable into operative position over said die, means for automatically moving said member over said bed, and braking means operating to prevent further movement of said member as it comes into operative position over said die, said means being so constructed and arranged that the extent of the movement of the pressure applying member out of operative position is independent of the extent of its movement into operative position.

11. A machine of the class described, comprising a bed, a pressure-applying member movable into various operative positions over said bed determined at the will of the operator, and means for automatically moving said member a predetermined distance 105 out of the selected operative position.

12. A machine of the class described, comprising a bed, a pressure-applying member movable into various operative positions over said bed determined at the will of the operator, and means for automatically moving said member out of its selected operative position constructed to effect a fixed amount of such movement.

13. A machine of the class described, comprising a stock supporting bed, a pressure-applying member movable at the will of the operator into various selected operative positions over stock supported on said bed, and means for automatically moving said member over said bed a distance sufficient to carry it out of position over the portion of the stock upon which the operator is working.

14. A machine of the class described, comprising a bed, a pressure-applying member movable at the will of the operator into and out of various selected operative positions thereover, and automatic means for effecting the movement of said member out of a se-

lected operative position constructed to move said member at uniform speed over said bed.

15. A machine of the class described, comprising a bed, a pressure-applying member movable at the will of the operator into and out of various selected operative positions thereover, and automatic means for effecting the movement of said member into its 10 various operative positions constructed to move said member at uniform speed over said bed.

16. A machine of the class described, comprising a bed, a pressure-applying member 15 movable at the will of the operator into various operative relations thereto and mechanism for automatically effecting the movement of said member into and out of a selected operative relation, said mechanism being constructed and arranged to move said member over said bed at uniform speed both into and out of the selected operative relation.

17. A machine of the class described, comprising a bed, a die movable over said bed at the will of the operator into various selected positions, a pressure-applying member movable into operative position over said die and means for automatically moving said member a predetermined distance out of operative position over said die, said means being so constructed and arranged that the extent of the movement of the pressure applying member out of operative position is independent of the extent of its movement into operative position.

18. A machine of the class described, comprising a bed, a die movable over said bed, a pressure-applying member movable into operative position over said die wherever located on the bed, and means for automatically moving said member out of operative position over said die constructed to effect the same amount of such movement from 45 each location of the die.

19. A machine of the class described, comprising a stock supporting bed, a die movable over stock supported on said bed into various selected positions, a pressure-applying member movable into operative position over said die wherever located on the bed and means for automatically moving said member over said bed a distance sufficient to place it out of position over the portion of 55 the stock upon which the operator is performing the die placing operation, said distance being the same from each location of the die.

20. A machine of the class described, comprising a bed, a die movable over said bed, a pressure-applying member movable into operative position over said die, means for automatically moving said member out of operative position over said die constructed 65 to effect a fixed amount of such movement,

and braking means arranged to operate automatically at the end of the movement of said member out of operative position.

21. A machine of the class described, comprising a bed, a die movable over said bed, a pressure-applying member movable into operative position over said die, means for automatically moving said member out of operative position over said die constructed to effect a fixed amount of such movement, 75 and braking means arranged to operate automatically at the end of the movement of said member into operative position.

22. A machine of the class described, comprising presser members relatively movable 80 into various operative relations to each other, means for effecting such relative movement and controlling means for said moving means comprising a device arranged to be moved by the operator, said means being so constructed that mere movement of the device in the desired direction and to the desired extent effects through said moving means a corresponding relative movement 85 of the presser members.

23. A machine of the class described, comprising a bed and a pressure-applying member movable into various operative positions thereover, a device movable by the operator into position over a portion of the surface 95 of said bed upon which it is desired that the pressure-applying member shall exert pressure, and means controlled by the movement of said device into the selected position for causing said member to be moved 100 automatically into operative position above the selected portion of the bed.

24. A machine of the class described, comprising a bed, a pressure-applying member movable into various operative positions 105 thereover, mechanism for automatically moving said member, and means arranged to be moved by the operator over said bed and so operatively related to said mechanism as to determine by the direction and extent of its movement the direction and extent of movement of said member.

25. A machine of the class described, comprising a bed, a pressure-applying member movable into various operative positions 115 thereover, mechanism for automatically moving said member, and means arranged to be moved by the operator over the bed and so operatively related to said mechanism as to effect by its movement in the desired direction and to the desired extent actuation of said mechanism to effect a movement of said member into a selected operative position.

26. A machine of the class described, comprising presser members relatively movable 125 into different operative relations to each other, mechanism for effecting automatically such relative movement, and controlling means for said mechanism comprising a de- 130

- vice arranged to determine by its movement in a selected direction and to a selected extent the amount of relative movement of said members by said mechanism.
5. 27. A machine of the class described, comprising a bed, and a pressure-applying member movable into different operative relations to said bed, means for automatically moving said member and controlling means for said moving means comprising a device arranged to determine by the direction and limit of its movement the direction and limit of the movement of said pressure-applying member by its moving means, and means for locking said device at the selected limit of its movement. 70
10. 28. A machine of the class described, comprising a bed, a pressure-applying member movable into and out of various operative positions thereover, mechanism for automatically moving said member, controlling means for said mechanism comprising an arm normally located above said member and arranged to be moved independently of said member by the operator in one direction and with said member in the other direction, and means for locking said arm at the selected limit of its movement by said operator. 75
15. 29. A machine of the class described, comprising a bed and a pressure-applying member movable into various operative relations to said bed, means for moving said member automatically into various selected relations, controlling means constructed and arranged to control both the actuation of said moving means and the extent and direction of movement of said member, and means for preventing actuation of said moving means except through said controlling means. 80
20. 30. A machine of the class described, comprising a bed, a pressure-applying member movable into and out of various operative positions thereover, mechanism for automatically moving said member and controlling means for said mechanism comprising a device normally in position above said member and arranged to be moved by the operator independently of said member in one direction and to be moved automatically with said member in the other direction. 85
25. 31. A machine of the class described, comprising a bed, and a pressure-applying member movable into various operative positions thereover, mechanism for effecting automatically movement of said member into and out of a selected operative position over said bed, and controlling means for said mechanism comprising a device movable independently of said member into the selected operative position and with said member out of the selected operative position. 90
30. 32. A machine of the class described, having in combination, a bed, a pressure-applying member movable into and out of selected operative relations to said bed, mechanism for automatically moving said member and controlling means comprising a device lying normally above said member, arranged to be moved independently of said member over said bed, and when so moved to effect an actuation of said mechanism to cause said member to be moved again beneath said device and then with said device in the opposite direction. 95
35. 33. A machine of the class described, having in combination, a bed, a die movable over said bed, a pressure-applying member movable into operative position over said die, mechanism for automatically moving said member, and controlling means for said mechanism comprising a device arranged to effect by its movement in either direction an actuation of said mechanism to move said member a distance proportional to the movement of said device. 100
40. 34. A machine of the class described, comprising a bed, a pressure-applying member movable into various operative positions thereover, mechanism for moving said member into and out of said operative positions, controlling means comprising a device arranged to be moved by the operator into position over a selected portion of said bed upon which it is desired that said pressure-applying member shall operate, and connections between said mechanism and said controlling means arranged to effect automatically an actuation of said mechanism as said device is moved into the selected position over said bed. 105
45. 35. A machine of the class described, comprising a bed, and a pressure-applying member movable into various operative positions thereover, a device movable by the operator into position over a portion of the surface of said bed upon which it is desired that the pressure-applying member shall exert pressure, and mechanism controlled by the movement of said device into the selected position for causing said member to be moved automatically into operative position above the selected portion of the bed, and effecting a pressure-applying operation of said member when the selected position has been reached. 110
50. 36. A machine of the class described, comprising a bed and a pressure-applying member movable into various operative positions thereover, a device movable by the operator into position over a portion of the surface of said bed upon which it is desired that the pressure-applying member shall exert pressure, and mechanism controlled by the movement of said device into the selected position for causing said member to be moved automatically into operative position above the selected portion of the bed, effecting a pressure-applying operation of said member when the selected position has been reached. 115
55. 37. A machine of the class described, comprising a bed, and a pressure-applying member movable into various operative positions thereover, mechanism for effecting automatically movement of said member into and out of a selected operative position over said bed, and controlling means for said mechanism comprising a device movable independently of said member into the selected operative position and with said member out of the selected operative position. 120
60. 38. A machine of the class described, having in combination, a bed, a pressure-applying member movable into and out of selected operative relations to said bed, mechanism for automatically moving said member and controlling means comprising a device lying normally above said member, arranged to be moved independently of said member over said bed, and when so moved to effect an actuation of said mechanism to cause said member to be moved again beneath said device and then with said device in the opposite direction. 125
65. 39. A machine of the class described, having in combination, a bed, a die movable over said bed, a pressure-applying member movable into operative position over said die, mechanism for automatically moving said member, and controlling means for said mechanism comprising a device arranged to effect by its movement in either direction an actuation of said mechanism to move said member a distance proportional to the movement of said device. 130

and after the pressing operation to be moved out of said position.

37. A machine of the class described, comprising a bed, a pressure-applying member movable into and out of various operative positions thereover, mechanism for automatically moving said member and controlling means for said mechanism comprising a device arranged to be moved by the operator into position over the selected portion of the bed upon which it is desired that said member shall operate and to effect by such movement an actuation of said mechanism to cause it to move said member into position over a selected portion of said bed, to effect a pressure-applying operation of said member, and then to effect a movement of said member out of the selected operative position, said device being also arranged to travel with said member out of the selected operative position.

38. A machine of the class described, comprising a bed, a pressure-applying member movable back and forth over said bed into various operative relations thereto and movable toward and away from said bed to perform a pressing operation, constantly operating mechanism, connections between said member and said mechanism including a clutch for effecting a movement of said member in one direction over the bed, connections including a clutch for moving said member in the other direction over said bed, connections including a clutch for moving said member toward and away from said bed, said clutches being arranged to operate in automatic succession, and a single means under control of the operator for controlling the order of clutching of said clutches.

39. A machine of the class described, comprising a bed, a pressure-applying member movable into various operative relations thereto, and mechanism for automatically effecting the movement of said member into and out of a selected operative relation, and an intervening pressure-applying movement, said mechanism being constructed and arranged to impart to said member a movement out of operative relation of uniform amount for successive operations.

40. A machine of the class described, comprising a bed, and a pressure-applying member movable into various operative relations to said bed, and mechanism for effecting automatically a movement of said member into a selected operative relation, actuation of said member to apply pressure and a return of said member to an inoperative relation, said mechanism being so constructed and arranged that the return movement is uniform for successive operations and independent of the amount of the initial movement.

41. A machine of the class described, having in combination, a bed, a die movable over

said bed, a pressure-applying member movable into and out of operative position over said die, mechanism for automatically effecting such movements of said member including means for effecting an intervening pressure-applying movement, said mechanism being constructed and arranged to effect a movement of said member out of operative position of uniform amount for successive operations of the machine.

42. A machine of the class described, comprising a bed and a pressure-applying member movable into various operative relations to said bed, mechanism for effecting automatically a movement of said member into a selected operative relation, actuation of said member to apply pressure and a return of said member to inoperative relation, said mechanism being so constructed and arranged that the return movement is uniform for successive operations and independent of the amount of the initial movement, and controlling means for predetermining the operative relation into which said member shall be automatically moved.

43. A machine of the class described, comprising coöperating pressing members relatively movable into different operative relations to each other and mechanism for effecting automatically relative movement of said members constructed and arranged to effect a relative movement of said members into a selected operative relation from any relation in which the members may happen to be and then a relative movement of constant amount out of said operative relation.

44. A machine of the class described, comprising coöperating pressing members relatively movable into different operative relations to each other, mechanism for effecting automatically relative movement of said members constructed and arranged to effect a relative movement of said members into a selected operative relation from any relation in which the members may happen to be and then a relative movement of constant amount out of said operative relation, and controlling means for determining in advance of the relative movement the operative relation into which the members shall be moved.

45. A machine of the class described, having in combination coöperating presser members relatively movable into and out of different operative relations to each other, automatic mechanism for effecting such movements comprising means for effecting a relative movement of said members into a selected operative relation from any relation in which the said members may be, means for effecting a relative pressure-applying movement of said members as they come into the selected operative relation, and means for effecting a relative movement of said members of a fixed amount for successive operations out of the selected operative re-

lation after said pressure-applying movement.

46. A machine of the class described, comprising a bed, a pressure-applying member movable into various operative positions thereover, means for moving said member in one direction over said bed, means for moving said member in another direction over said bed, means for causing said member to apply pressure and controlling means comprising a device movable by the operator into position over a portion of the surface of said bed upon which it is desired that the pressure-applying member shall exert pressure, said controlling means being so operatively related to the several means for moving said pressure-applying member and being so constructed and arranged that when said device is moved by the operator into the selected operative position over said bed it effects an actuation of the means which moves the pressure-applying member in the direction in which said device has been moved, and through said means actuation of the means to cause said member to apply pressure, and through said last-named means actuation of the means for moving said member in the other direction over said bed.

47. A machine of the class described, comprising a bed and a pressure-applying member movable thereover into and out of operative position, means for moving said member into and out of operative position comprising reversely moving parts, controlling means for effecting an operative connection between one of said moving parts and said member according to the direction in which it is desired that said member shall move, said means being constructed and arranged to cause an interruption of said connection after a predetermined amount of movement of said member, and means arranged to be actuated upon the interruption of said connection for effecting an operative connection between said member and the other of said moving parts.

48. A machine of the class described, comprising a bed, a vertical column having attached thereto a radial pressure-applying member adapted to be rotated with said column into different pressure-applying relations to said bed, a gear on said column, normally rotating intergeared vertical shafts, gears loose on the respective shafts, arranged to be separately clutched thereto and in mesh with said first-mentioned gear, means for clutching said loose gears to and unclutching them from the respective shafts in succession, and means for controlling the order of operation of said clutching means.

49. A machine of the class described, comprising a bed, a pressure-applying member movable into various operative relations thereto, mechanism for automatically mov-

ing said member, braking mechanism for checking the movement of said first-mentioned mechanism after said member has been moved into a selected operative relation, and means for effecting an actuation 70 of said moving mechanism constructed and arranged to effect an actuation of said braking mechanism as said member comes into said operative relation.

50. A machine of the class described, having in combination, a bed, a die movable over said bed, a pressure-applying member movable into and out of operative position over said die, mechanism for automatically moving said member, braking mechanism, 75 and means for effecting an actuation of said moving mechanism constructed and arranged to effect an actuation of said braking mechanism after said moving mechanism has effected a movement of said member into position over said die.

51. In a machine of the class described, the combination with a driving member and a driven member, of a clutch for connecting said members, means for operating said 90 clutch constructed to effect a clutching of said members for a movement proportional to the movement of a part of said means and other means for operating said clutch constructed to effect a clutching of said 95 members for a single rotation.

52. In a machine for dieing out leather for boots and shoes, the combination of a cutting bed, a presser member freely movable laterally over said bed into operative 100 position, and means acting to automatically move the presser member laterally into inoperative position.

53. In a machine for dieing out sheet leather for boots and shoes, the combination 105 of a bed, a presser member, means for moving the presser member toward and from the bed, and means permitting free lateral movement of the presser member into operative position over the bed and acting after 110 a dieing out operation to move the presser member laterally into inoperative position.

54. In a machine of the character described, the combination of a bed, a presser member, means for moving the presser member at right angles to the surface of the bed, means permitting free movement of the presser member laterally into operative position opposite the bed, and means acting during the movement of the presser member at 115 right angles to the surface of the bed for causing said last-named means to become effective to move the presser member laterally from operative position with respect to the bed.

55. In a machine for dieing out leather, the combination of a bed, a presser member, means to move the presser member toward and from the bed to press upon the die or cutter, power actuated means for moving the 130

presser member laterally into inoperative position with respect to the bed, and mechanism for operatively connecting and disconnecting said power actuated means and 5 presser member to permit the said presser member to be freely movable laterally to operative position and to move the presser member laterally into inoperative position.

56. In a machine of the character described, the combination of a cutting bed, 10 a presser member freely movable laterally into operative position with relation to said bed, a shaft, connections between said shaft and presser member for moving it toward 15 and from the bed, and means controlled from said shaft for automatically moving the presser member laterally into inoperative position.

57. In a machine for dieing out leather,

the combination of a supporting frame, a 20 shaft mounted thereon, a cutting bed, a spindle, connections between the spindle and shaft for moving the spindle vertically, a presser column mounted to move with and turn on said spindle, a presser arm carried 25 by said column, and means permitting free rotative movement of the presser arm into operative position with relation to the bed and acting to automatically return it to inoperative position to one side of the bed. 30

In testimony whereof I have signed my name to this specification in the presence of two subscribing witnesses.

IRA C. BUCKMINSTER.
